CONTINUOUSLY MOVING BALLAST REMOVING MECHANISM

Martin J. Speno, Syracuse, N.Y., assignor to Frank Speno
Railroad Ballast Cleaning Company, Inc., Ithaca, N.Y.,
a corporation of New York

Filed Dec. 8, 1965, Ser. No. 512,460
15 Claims. (Cl. 37—104)

ABSTRACT OF THE DISCLOSURE

Mechanism for automatically removing dirty ballast from between the adjoining ties of a railroad track, in which a portable vehicle movable along the track carries a plurality of probes for vertical projection and retraction movement into the ballast between the cribs. Proximity switches actuated by the tie plates of the respective ties, control solenoid actuated valves which, in turn, cause the probes to be projected downwardly into and withdrawn from the crib spaces as the vehicle moves along the track. The probes are provided with cam faces to laterally displace the ballast and also are provided with laterally directed jet nozzles for emitting jets of pressurized fluid for laterally displacing the ballast.

This invention relates to mechanism for automatically removing dirty ballast from the cribs or spaces between relatively adjoining ties of a railroad track.

It has been heretofore known to employ a mechanical means for digging or raking the ballast outwardly from the cribs. However, such a mechanical means has either necessitated the lifting or raising of the rails or else has involved extremely heavy and complicated parts. Similarly, it has heretofore been known to employ blasts of fluid such as gases or liquids under high pressures for removal of the ballast. However, in so doing, difficulty has been encountered in securing the desired degree of penetration of the packed ballast, as well as in controlling the depth, shape and extent of the resulting excavation.

With these considerations in mind, the primary objects of the present invention are to combine both of said old principles in a single mechanism which accordingly employs a mechanical digging and lateral displacing action in combination with a blast jet or jets of fluid at high pressure to remove the ballast from the cribs in a particularly efficient and rapid manner; to provide such a mechanism which is adapted for removal of ballast from successive cribs while in constant motion along the track, without damage to the ties; to provide such a mechanism wherein the mechanical digging or excavating means is automatically projected downwardly into each crib to a predetermined depth and rapidly retracted during its movement between each pair of adjacent ties.

Further, it is an object to provide each of the mechanical digging or excavating members of the mechanism with one or more laterally directed jet orifices and means for delivering fluid therethrough at high pressures and velocities during the penetration of such member into the ballast whereby to propel or displace the ballast outwardly laterally for reception alongside the pump track, preferably in a preformed ditch or trench paralleling the track. It is a further object to provide means for auto-

2

matically discontinuing the said blast jet as its associated probe or excavating member is retracted.

Still further it is an object to employ a plurality or gang of the said probes or members in series, so as to follow each other in relatively laterally offset relation, preferably at uniform lateral distances, with each probe displaced uniformly laterally inwardly from the probe immediately in advance thereof in the direction of travel of the ballast removing car or vehicle, so that the ballast will be removed from each crib in successive increments from the outer extremity inwardly thereof. It is also an added feature to provide the respective probes with inclined cam faces arranged to mechanically displace the ballast laterally outwardly incident to their penetrating movement into the ballast.

The foregoing and other incidental objects and advantages will all be readily apparent from a consideration of the following detailed description, together with the accompanying drawings of a preferred embodiment of the invention in which:

FIGURE 1 is a view in perspective, showing a portion of a conventional railroad flatcar and of the underlying conventional railroad track upon which it is guided, a preferred exemplification of the invention being supported from the car for operation on the ballast between the outer ends of the ties;

FIGURE 2 is a vertical cross section through the structure shown in FIGURE 1;

FIGURE 3 is a view partly in plan and partly in section on the line 3—3 of FIGURE 2, showing the relatively offset or staggered relationships of the ballast removing members or probes;

FIGURE 4 is an enlarged diagrammatic view, partly in section and partly in elevation, showing the hydraulic and electrical control circuits and valve means employed in conjunction with each of the said probes; and

FIGURE 5 is a detail elevation on the line 5—5 of FIGURE 4, showing a typical disposition of the jet defining orifices in the lower ballast penetrating end portion of the probe.

To promote an understanding of the invention, reference will now be made to the preferred embodiment thereof illustrated in the accompanying drawings, and specific language will be used to describe the same. It will nevertheless be appreciated that no limitation of the scope of the invention is thereby intended, but that such further modifications and alterations are envisioned as would normally occur to one skilled in the art to which the invention relates.

Referring now to the accompanying drawings, there is illustrated in FIGURES 1 and 2 a fragmentary portion only of a conventional flatcar 10, including a portion of the side rail 11 and of the flat load carrying bed 12 thereof. As is well known, such a car is normally supported and guided for movement along the railroad track by conventional flanged wheels (not shown), each which is adapted for engagement with a rail 13 of the track.

The rails 13 are secured by conventional tie plates T on cross ties 14 which are partially embedded in the ballast 15. The ballast generally consists of crushed stone, or the like, which over a period of time tends to become intermixed with dirt and foreign material which clogs the interstices between adjoining stone particles to an

extent which interferes with proper drainage and otherwise is undesirable.

It is accordingly the practice to remove, clean and replace the dirty ballast whereby to restore the roadbed to its proper operative condition. While the ballast alongside the outer ends of the ties may readily be removed by conventional scoop means, transported along the tracks in a manner to remove such ballast and to leave a trench along the tracks to be subsequently filled by clean ballast, the present invention is directed to the more difficult problem of removing dirty ballast from the cribs or spaces between the adjoining ties. The mechanism here illustrated is especially adapted for removing such ballast from between the outer ends of the ties, laterally outwardly of the rails, though it is by no means restricted to use in ballast removed at this location.

Generally speaking, the invention is embodied in one or more probes 16, guided for rapid vertical penetration into and withdrawal from the cribs by means of fluid-pressure actuated cylinders 17, here shown as carried by common rigid frame bar 18 supported from the flatcar 10 in a normally stationary position. Preferably the bar 18 is carried by a series of vertical guide rods 20 which are telescopically received within the guide sleeves 21 respectively for vertical adjustment of the frame 18. For the purpose of lateral adjustment, the respective sleeves 21 are each supported by a horizontal guide rod 22 for telescopic sliding reception in a guide sleeve 23 supported from the bed 12 of the car by a suitable bracket 24. The vertical guide sleeves 21 are interconnected by rigid longitudinal bar 25, through which lateral adjustment is transmitted to the sleeves 21 and frame 18 from a suitable hydraulic, pneumatic or other conventional power actuated means, through the rigid links 26 having their clevises 27 connected to cooperating arms 28 affixed to the bar 25.

As will be apparent from FIGURES 1 and 2, the cylinders 17 of the respective fluid pressure actuated means or devices are supported from the frame bar 18 by rigid horizontal arms 30 respectively. Fluid actuated cylinder and piston units 31-31, operatively interconnected between certain of the arms 30 and rigid arms 32 of the connecting bar 25, exemplify convenience means for selectively adjusting the vertical position of the frame 18 and securing it in the desired position of adjustment. Thus the entire gang of probes 16 supported from the frame 18 may be vertically and horizontally adjusted to any of various desired operative positions relative to the roadbed. For transport purposes, the frame 18 normally will be fully raised by action of the piston and cylinder units 31 and displaced or drawn laterally inwardly closely adjacent to the side sill 11 by traction forces transmitted through the connecting rods or links 26.

Referring now to FIGURE 4, in conjunction with FIGURES 1 and 2, each probe 16 in the present embodiment comprises a rigid hollow tube, terminating at its lower ballast engaging and penetrating end in a comparatively sharp edge 34 adapted to facilitate its penetration of the ballast. Preferably, each probe has a vertically inclined cam face 35 sloping upwardly and outwardly, away from the rail 13, so that it will tend to mechanically displace the ballast in a laterally outwardly direction for reception in the trench D adjacent to the outer ends of the ties. Opening outwardly through this cam face 35 are one or more orifices 36 communicating with its hollow interior and adapted to be supplied with pressurized fluid such as steam, compressed air, exhaust gases of a jet engine or the like, whereby laterally directed jet streams will be caused to issue at high velocity through the respective orifices to propel the ballast outwardly from the cribs and into trench D.

In the present embodiment, the shank 37 of each probe 16 extends and is slidably completely through the opposite ends of its associated cylinder 17, whereby fluid at the desired pressures and in the desired volume may be

readily supplied through the hollow interior of each probe 16 to its orifices 36 by means of a flexible conduit 38 clamped to the upper end of its shank 37 as at 39.

The shank 37 is encircled by and fixedly connected to the annular piston 40 which in turn is disposed for movement in the cylinder 17 in snug fluid-tight sliding engagement with its inner peripheral walls, whereby vertical movement may be imparted to the probe 16 by fluid pressure within the cylinder acting against the piston. The pressurized fluid for causing the downward stroke of the piston 40 is admitted into the cylinder 17 above the piston through one or more constantly open ports 42 opening radially outwardly from the hollow interior of the probe shank 37 above the piston. Thus the same pressurized fluid which is delivered through the hollow shank 37 to the jet orifices 36 will provide the actuating pressure for the downward or penetrating stroke of the piston 40 and probe 16 simultaneously with the opening of a valve or the like for permitting flow of the pressurized fluid to the probe 16.

The raising or retraction stroke of the probe 16, which occurs only after the discontinuance of the fluid supply through the hollow probe shank 37, is produced by introduction of pressurized fluid into the lower end of the cylinder 17 beneath the piston 40 through the inlet passage 43, the port 42 then serving as an exhaust port. For permitting the exhaust of gases from the lower portion of the cylinder during the down stroke of the piston 40, the inlet port 43 is in communication with an exhaust port 44, through a shuttle valve 45 which is normally biased by the spring 46 to a position in which it places the passages 43 and 44 in communication with each other. However, the fluid pressure for raising or retracting the piston 40 is delivered to its inlet passage 43 through a flexible conduit 47 which communicates with the shuttle valve 45 in a known manner such that the pressure of fluid when admitted to the conduit 47 moves the valve 45 downwardly to compress its spring 46 and to close the exhaust passage 44, while placing the conduit 47 in communication with the inlet 43. It will be appreciated that immediately upon cessation of the fluid pressure within the conduit 47, the spring 46 will return the valve 45 to its original position to permit exhaustion of the fluid from the lower portion of the cylinder incident to the next downward stroke of the piston 40.

Preferably the flexible fluid conduits 47 and 38 are arranged for alternate communication through the control valve 48, with a supply line or manifold 53 for fluid under pressure. The valve 48 is controlled by solenoids in the manner taught in the United States patent of McGuire 1,024,250 of Aug. 29, 1933. Thus the body of the valve 48 is positioned by means of its stem 49. A compression spring 50, reacting between an enlargement 51 on the stem 49 and the valve housing, normally biases the valve to a position in which a supply of fluid from the line 53 or other suitable source of such fluid under pressure is delivered to the conduit 47 to maintain fluid pressure beneath the piston 40 and thus to normally maintain the piston 40 and its associated probe 16 in fully raised position. The valve stem 49 is of a magnetizable material. It constitutes the core of a solenoid, the winding 54 of which is energized under the control of a generally conventional and normally open proximity switch 55 which is carried by the frame 18 for movement in a path 56 which extends above the respective tie plates T and in such trailing relation to its associated probe 16 as to be closed by its proximity to each tie plate as or shortly after the probe 16 is carried over and free of the particular tie 14 with which the said tie plate is associated. The switch 55 remains thus closed throughout the duration of its movement above the tie plate, whereupon it will automatically open in a manner well known to those skilled in the art, the switch being actuated by the magnetic attraction of the tie plate, or if desired by physical contact with the tie plate.

In the preferred embodiment, the switch 55 is carried by a bracket 56, which is laterally positioned on the track by means of a roller 57 having flanges at its opposite ends to effect such positioning. The said bracket or carriage is propelled along the rail 13 by virtue of its connection through a cross pin 58 to a depending coupling member 60 carried by the frame bar 18. The cross pin 58 is freely slideable through the member 60 to afford freedom of lateral movement so that the lateral position of the switch 55 at one side of the rail may be accurately determined by its flanged roller 57.

Thus, as the proximity switch 55 for a given probe 16 is closed incident to its passage over a tie plate T, the probe 16 will have cleared the tie. The ensuing energizing of the solenoid coil 54 and the action thereof on the valve stem 49 moves valve 48 to disrupt the communication between the supply conduit 53 and the retraction conduit 47 and to place the supply conduit 53 in communication with the conduit 38, thereby simultaneously initiating the operative downward stroke of the piston 40 through the entry of pressurized fluid into the upper portion of the piston through inlet ports 42, and also the discharge of jets of pressurized fluid at high velocity through the orifices 36 of the probe. The valve 48 will be latched into its said position by the reception of the spring projected latch member 63 in its coacting latching notch 64. The latch member 63 constitutes the movable core of a solenoid 65 from which the latch 63 is normally spring projected to latching engagement with the valve stem 49.

The circuit 66 to and through the solenoid 65 is controlled by limit switch 67 positioned on the bottom of the cylinder 17 so as to be closed by the downwardly moving piston 40 at the lower end of its operative stroke. Thus, closing of the limit switch 67 at the lower end of the piston stroke 40 will energize the coil of solenoid 65 to retract the latch 63, thereby permitting return of the valve 48 under the action of its valve spring 50 to its original position in which the fluid supply conduit 53 is disconnected from the conduit 38 and placed in communication with the retraction conduit 47. The shuttle valve 45 which will have been positioned by spring 46 to permit exhaust of fluid from the lower portion of the cylinder during its down stroke, will now be actuated by the fluid pressure in conduit 47 to place said conduit in communication with the lower portion of the cylinder through passage 43, while closing off the exhaust passage 44. Such pressure beneath the piston 40 will cause the upward retraction of the probe 16, the fluid in the upper portion of the cylinder then being exhausted into the hollow probe shank 37 through the port 42 and discharged through the orifices 36.

It is to be understood that the various parts will so be proportioned and interrelated that the downward stroke of the probe and its upward retraction will occur quite rapidly, while the flatcar 10 is moving along the rails at a rate of speed, and without interruption of such movement. In other words, the rejection and retraction stroke will be timed to occur during the interval required for movement of the probe 16 across the space from one tie to the next and will normally allow ample margin for action between irregularly spaced or unusually closely spaced ties.

Subsequent to each retraction, a given probe 16 will remain raised during passage over the next tie, due to the continuing transmission of fluid pressure to the lower portion of its cylinder 17, the position of the valve 48 remaining unchanged until its solenoid 54 is again energized by the proximity switch 55 in passing over the tie plate T of the next tie. As will be apparent, the leading probe 16 with respect to the movement of the flatcar 10 (as indicated by the arrow in FIGURE 1) is spaced laterally outwardly from the side of the car 10 for movement in a path near the outer extremities of the ties 14 and just inwardly from the adjoining vertical edge of the trench D. The trailing probes 16 are supported

in positions successively closer to the car 10 and thus are successively placed inwardly at progressively greater distances from the ends of the ties and the adjacent wall of trench D. It will be appreciated that each probe is automatically actuated independently of the others, so that each in turn will act upon all cribs, and that the several probes will each remove from a given crib an increment or portion of the ballast, whereby the several probes, by their successive action on each crib, will remove the total intended amount of ballast therefrom in successive increments of substantially uniform size and to a uniform depth, corresponding to the uniform depth to which the probes 16 are projected on their penetrating or downward stroke.

Such depth of penetration for all of the several probes may be controlled or regulated by appropriate position of their supporting frame bar 18, by means of the fluid actuated cylinder and piston units 31. Similarly, the lateral position of the frame 18 and thus the lateral operating positions of the probes 16 may be adjusted toward and away from the rail 13 as desired.

The actuation of the several probes 16 thus is automatically initiated immediately after each probe passes over a tie. The ensuing downward projection of the probe and actuation of its blast jets, and the subsequent retraction of the probe, occur substantially instantaneously so that the probe will be raised clear of the next tie to pass thereover before being again actuated. Thus, the probes 16 normally will be guided and actuated in such a manner as to avoid collision with the ties. However, as an added safeguard, the probes 16 are each connected to its respective shank 37 along an encircling weakened zone, such as 68 in FIGURES 4 and 5, located just below the internal check valve seat 69. A ball check valve 70 is supported above the seat 69 by a bracket 71 secured to the inner wall of the probe 16. In the event of breaking away of the probe along weakened zone 68, the ensuing seating of the check valve 70 will prevent the uncontrolled escape of the pressurized gas from the lower end of shank 37.

As has been above indicated, the foregoing detailed description and accompanying drawings, through directed specifically to the preferred embodiment of the invention, are merely by way of exemplification of the invention, and various changes and departures from such preferred embodiment are contemplated within the scope of the appended claims.

Having thus described my invention, I claim:

1. Mechanism for automatically removing ballast from between adjoining ties of a railroad track, comprising a portable vehicle adapted for movement parallel to the rails of said railroad track, a rigid supporting frame on said vehicle, a plurality of probes supported by said frame for vertical projection and retraction movement into and from penetrating engagement with the ballast in the crib spaces between adjacent cross ties of the track, fluid pressure actuated means for raising and lowering the respective probes, valve means for controlling said fluid pressure actuated means, sensing means operative in response to the movement of each said probe into vertical registry with a crib space for rapidly downwardly projecting and retracting said probe during its movement in registry with said space, and means for retaining said probe in its raised position until again actuated by said sensing means incident to its movement with the portable vehicle into vertical registry with a further crib space, said sensing means comprising a proximity switch carried by said vehicle for movement along a path overlying the tie plates of the respective ties and in predetermined trailing relation to its associated probe, to be closed incident to passing over each tie plate, and solenoid means operatively connected to and controlling said valve means, said solenoid means being in circuit with and controlled by said sensing means.

2. Automatic mechanism as recited in claim 1, in which

each said probe is provided with a sharpened lower end for penetration of the ballast and with a cam face presented outwardly away from the said vehicle, said cam face being inclined upwardly and laterally outwardly to displace the ballast laterally outwardly incident to penetration thereof by the said probe.

3. Mechanism for automatically removing ballast from between adjoining ties of a railroad track, comprising a portable vehicle adapted for movement parallel to the rails of said railroad track, a rigid supporting frame on said vehicle, a plurality of probes supported by said frame for vertical projection and retraction movement into and from penetrating engagement with the ballast in the crib spaces between adjacent cross ties of the track, fluid pressure actuated means for raising and lowering the respective probes, valve means for controlling said fluid pressure actuated means, sensing means operative in response to the movement of each said probe into vertical registry with a crib space for rapidly downwardly projecting and retracting said probe during its movement in registry with said space, and means for retaining said probe in its raised position until again actuated by said sensing means incident to its movement with the portable vehicle into vertical registry with a further crib space, said sensing means comprising a proximity switch carried by said vehicle for movement along a path overlying the tie plates of the respective ties and in predetermined trailing relation to its associated probe, to be closed incident to passing over the tie plate, and solenoid means operatively connected to and controlling said valve means, said solenoid means being in circuit with and controlled by said sensing means, said plurality of probes being arranged in relatively staggered relation, with the leading said probe relative to the direction of the vehicle movement being supported at a maximum lateral distance outwardly from the said supporting frame, and the other said probes being successively located in a manner such that each is inwardly laterally displaced with respect to the probe in advance thereof, said fluid pressure actuated means for raising and lowering the respective probes being independently operable with respect to each said probe, whereby the said plurality of probes will act in succession upon each crib space to remove ballast therefrom in successive increments from the outer end of the crib space inwardly toward the rail.

4. Automatic mechanism as recited in claim 3, wherein each said probe includes a laterally outwardly directed jet nozzle adjacent its lower end and means for supplying pressurized fluid to said nozzle for issuance therefrom as a jet for displacing the ballast on the outer side of said probe.

5. Automatic mechanism as defined in claim 1, in which each said probe is provided with an orifice opening laterally outwardly through its lower end and a fluid supply passage communicating with said orifice, means being provided for supplying pressurized fluid to said passage for emission through said orifice in the form of a laterally outwardly directed fluid jet.

6. Automatic mechanism as defined in claim 5, including means operative in the raised position of said probe for discontinuing the flow of fluid to said orifice.

7. Mechanism for automatically removing ballast laterally outwardly from the cribs of a railroad track, comprising a portable vehicle adapted for movement along and parallel to the rails of the track, a supporting frame carried by said vehicle, a plurality of probes supported by said frame for independent vertical downward projection and retraction whereby to cause their lower ends to penetrate the ballast in the cribs to predetermined uniform depth, fluid pressure actuated means for raising and lowering the respective probes, valve means for controlling the projection and retraction of each probe, sensing means operatively connected with each said probe means for initiating the projection stroke of the probe each time the same reaches a position of vertical registry

with a crib, each of said probes being provided adjacent its lower end with a laterally directed orifice and including a passage for conducting pressurized fluid to said orifice, and means for supplying fluid at high pressure to said passage for ejection through said orifice to be discharged therethrough in the form of a laterally outwardly directed jet stream.

8. Automatic mechanism as defined in claim 7, including valve means controlling the flow of fluid through said passage, said valve means being operatively connected to said sensing means to be opened during each downward projection of the probe.

9. Automatic mechanism as defined in claim 8, including means controlled by said projection of the probe for closing said valve means to discontinue said fluid jet at a predetermined point in the downward projection stroke of the probe.

10. Automatic mechanism as defined in claim 7, in which said fluid pressure actuated means for each said probe comprises a fluid actuated piston and cylinder unit in which the probe is carried by the piston thereof.

11. Automatic mechanism as defined in claim 10, in which said sensing means comprises a proximity switch carried by said vehicle for movement along a path overlying the tie plates of the respective ties and in predetermined trailing relation to its associated probe, to be closed incident to passing over the tie plate, solenoid means operatively connected to and controlling said valve means, said solenoid means being in circuit with and controlled by said sensing means.

12. Automatic mechanism as defined in claim 11, in which said valve means for controlling the fluid pressure actuated means, and said valve means for controlling the flow of pressurized fluid to the orifice of said probe, both comprise a valve common to both said fluid pressure actuated means and said valve means.

13. Automatic mechanism as defined in claim 11, including a normally open limit switch in position for operative engagement by said piston near the lower extremity of its downward movement, and means for closing the said valve means to permit retraction of the said probe, said means including a solenoid having a coil in circuit with said limit switch.

14. Automatic mechanism as defined in claim 13, including means defining and alternately acting inlet and discharge passage communicating with the lower end portion of said cylinder beneath the piston therein, a shuttle valve normally spring biased to a position to place said passage in communication with the atmosphere, a fluid supply conduit communicating with said shuttle valve and arranged to apply fluid pressure against said valve for actuating same to close said exhaust passage and to place said supply passage in communication with the inlet passage, and a solenoid valve having a control switch positioned for actuation by said piston near the lower end of the stroke for admitting pressurized fluid to such supply passage for retracting the said piston.

15. Mechanism for operating automatically and successively on fixed components of a railroad track structure, comprising a carrier disposed for movement along said structure, a tool supported by said carrier for movement transversely to the movement of the carrier for successive operative engagement with and disengagement from said components, fluid pressure means for so moving the tool relative to said components, valve means for controlling said fluid pressure means, sensing means actuated in response to the positioning of said tool adjacent each said component incident to movement of the carrier for thus transversely moving the tool relative to each of said components in succession, and means for retaining said tool disengaged from said components between actuations of the sensing means, said sensing means comprising a proximity switch carried by said vehicle for movement along a path overlying the tie plates of the respective ties and in predetermined trailing relation to its said tool,

to be closed in response to passing over each tie plate, and solenoid means operatively connected to and controlling said valve means, said solenoid means being in circuit with and controlled by said sensing means.
